UNITED STATES PATENT OFFICE.

EDWARD R. PENROSE, OF LOGANSFORT, INDIANA, ASSIGNOR TO BUDA COMPANY, OF CHICAGO, ILLINOIS, A CORPORATION OF ILLINOIS.

LIFTING-JACK.

1,078,374.

Specification of Letters Patent.

Patented Nov. 11, 1913.

Application filed March 17, 1913. Serial No. 754,774.

To all whom it may concern:

Be it known that I, EDWARD R. PENROSE, a citizen of the United States, and residing at Logansport, in the county of Cass and State of Indiana, have invented certain new and useful Improvements in Lifting-Jacks, of which the following is a specification, reference being had to the accompanying drawings.

10 My invention relates generally to the class of lifting jacks, and more particularly to the application of an improved thrust and friction mechanism in a jack casing, wherein the degree of frictional resistance is proportional 15 to load pressure.

This invention has for its principal object the provision of certain means more specifically set forth hereinafter, whereby the jack screw is positively prevented from accidentally running down in the jack under a load.

This, together with such other objects as may hereinafter appear, or are incident to my invention, I attain by means of a construction illustrated in preferred form in the 25 accompanying drawings, wherein:

Figure 1 is a vertical section of a lifting jack embodying my invention.

Figure 2 is a sectional view on the line II—II of Figure 1, and

30 Figure 3 is a partial view in perspective showing the engagement of a pawl with the gear teeth.

In practice it frequently happens that a jack of this character while sustaining a 35 heavy load will run down bringing the load with it, and it is obvious that such accidental lowering is an objectionable feature. It is my object to overcome this by providing an independent annular member removed from the upper face of the gear by a plurality of 40 anti-friction members, said member being provided with a depending annular flange or lug carrying a pawl which rides over the gear teeth so that the gear freely rotates in one direction, while on rotation in the opposite direction the annular member has synchronous movement with the gear through the engagement of the pawl with the gear teeth, whereby accidental lowering of the 45 screw and shell is effectually and positively prevented.

In describing my invention the numeral 4 indicates a stationary standard with its supporting base 5, and having a close fit about 50 the standard for relative movement there-

with is a shell 6, its upper end being inclosed to form a cap 7. Within the upper end of the standard is mounted the usual operating nut 8 carrying the screw 9. The latter has keyed to its upper reduced end a bevel gear 10 60 which meshes with a bevel pinion 11 formed upon the stub shaft 12, the shaft being journaled in the shell and adapted to receive rotation from any suitable operating mechanism 13 to raise and lower the jack, as will be 65 understood.

Interposed between the upper face of the gear and the cap 7 of the shell is an annular bearing plate 14 having an annular depending flange 14^a, and between these two members are interposed a plurality of anti-friction members 15. Positioned between the plate 14 and the shell cap is a friction disk 16.

The numeral 17 represents a plurality of 70 pawls mounted in suitable recesses in the inner walls of the depending flange 14^a for engagement with the gear 10, each pawl having movement on its pivot pin 18 and yieldingly held against the gear teeth by a spring 19 within the recess. The gear 10 preferably 75 has the faces of its teeth relatively wider than those of the bevel pinion 11, the pitch line of the teeth in such case being carried up vertically a comparatively short distance as shown at 10^a in Figures 1 and 3, so that 80 whatever position the pawls may subsequently occupy with respect to the periphery of the gear they may all have positive engagement with the teeth.

From the foregoing it will be apparent 90 that when the bevel gear 10 is rotated to rise in the jack by means of the pinion 11 and operating mechanism 13, the pawls 17 ride easily over the teeth of the gear so that it freely rotates to lift the shell relative to the 95 standard to raise a load.

The jack may safely be left at any time during the operation of lifting the load, or when the load has been raised to its predetermined position, as any reverse rotary 100 movement of the gear due to load pressure and leading to the accidental running down of the screw and shell, is effectually prevented by the annular member 14 through its pawls 17 which have positive engagement 105 with the gear teeth. Under these circumstances the member 14 is stationary as the frictional resistance due in part to the interposition of the friction disk, overcomes any tendency to reverse rotary motion of 110

the gear. This is particularly advantageous in high-speed jacks where a coarse threaded screw is employed for quick running up of the load.

5 In lowering the load the mechanism 13 is operated to overcome the frictional resistance above referred to, the gear 10 and annular member 14 having synchronous rotative movement during this operation, which 10 insures a degree of safety not otherwise obtained. The direct engagement between the bearing plate pawls and the teeth of the gear is an advantageous feature, and is further promotive of an economical and 15 simple arrangement of a few parts leading to a maximum degree of efficiency.

From the foregoing, the essential features, elements and the operation of the device, together with its simplicity and other advantages thereof, will be clearly apparent.

Having thus described my invention and illustrated its use what I claim as new and desire to secure by Letters Patent is the following:

25 1. In a lifting jack, the combination of a standard and a member movable thereon, a screw for said movable member provided with a gear, an annular member interposed between said gear and said movable member, and means carried by said annular member adapted to engage with the teeth of the gear for synchronous movement of the said member and gear in the one direction, the said means permitting the gear to have 30 free and independent movement in the other direction.

2. In a lifting jack, the combination of a standard and a movable member thereon, a screw for said movable member and provided with an actuating gear, an annular member between said gear and said movable member in frictional contact with the latter, and a pawl carried by the said annular member adapted to engage with the teeth of the gear whereby the said gear and annular member have similar movement in one direction, but permitting independent movement of the gear in the other direction.

45 3. In a lifting jack, the combination of a

standard having a member movable thereon, a screw for said movable member, a gear mounted on the screw, and an annular plate between the movable member and gear provided with a depending portion terminating below the upper face of the gear, and means 55 interposed between said depending portion and gear adapted to engage the teeth of the latter for synchronous movement in one direction, but permitting the gear to have independent movement in another direction, 60 substantially as described.

4. In a lifting jack, a standard and a movable member thereon, a screw and nut for raising and lowering the movable member, means for rotating said screw comprising a 65 pair of gears having relatively different sized teeth widths, an annular plate interposed between the screw and the movable member, and a pawl carried by the annular member and adapted to connect it with the gear having the greater width of teeth for similar rotation of these members when lowering the jack, the excess in teeth width of the last mentioned gear permitting a continuous connection between the gear teeth and the annular plate irrespective of any position taken up by the pawl.

70 5. A lifting jack comprising in combination a standard, a shell movably mounted on the standard, a screw threaded into the 75 standard for lowering and raising the shell, a bevel gear on the screw having teeth extending from face to face of the gear, an annular plate interposed between the gear and the shell, a pawl carried by the plate 80 having a ratchet engagement with the teeth adjacent the largest diameter face of the gear, and a second bevel gear for turning the first gear engaging the teeth of the first gear adjacent the smaller diameter face 85 thereof.

90 In testimony whereof I have hereunto signed my name in the presence of the two subscribed witnesses.

EDWARD R. PENROSE.
